THERMOSTATIC ELECTRIC CONNECTOR PLUG

Melvin H. Boldt, Glenview, Ill., assignor to National Presto Industries, Inc., Eau Claire, Wis.

Filed Oct. 21, 1971, Ser. No. 191,581

Term of patent 14 years

Int. Cl. D13—03

U.S. Cl. D26—13 R

FIG. 1

FIG. 2

FIG. 3

FIG. 4

FIG. 5

FIG. 1 is a top plan view of a thermostatic electric connector plug, showing my new design;

FIG. 2 is a side elevational view thereof, the opposite side of the thermostatic electric connector plug being a mirror image thereof;

FIG. 3 is a bottom plan view thereof;

FIG. 4 is a front end view thereof; and

FIG. 5 is a rear end view thereof.

The broken lines are for illustrative purposes only.

I claim:

The ornamental design for a thermostatic electric connector plug, substantially as shown and described.
